UNITED STATES PATENT OFFICE.

PIERRE DONON, OF PARIS, FRANCE, ASSIGNOR TO ETABLISSEMENTS BAUDET & DONON, OF PARIS, FRANCE.

CHANGE-SPEED DEVICE.

Application filed November 26, 1921. Serial No. 517,901.

To all whom it may concern:

Be it known that I, PIERRE DONON, a citizen of the French Republic, residing at 139-141 Rue Saussure, Paris, France, have 5 invented certain new and useful Improvements in Change-Speed Devices, of which the following is a specification.

This invention relates to a change-speed device with two combinations wherein a 10 double-faced clutch member is keyed to the main actuated shaft between two gear wheels of different diameters mounted loose on the said shaft. A common gear wheel continually drives both the said gear wheel, in one 15 case through an intermediate pinion and in the other case by direct drive. This group of three gear wheels is provided with a double side-shifting device whereby one or the other of the two gear wheels mounted 20 loose on the main actuated shaft may be caused to engage the said clutch member.

The said change-speed device may be readily mounted at the outgoing end of an ordinary change-speed device having for instance four or six speeds, and is in this case actuated either by a pinion keyed to the outgoing shaft of the box and directly engaging the two loose gear wheels of the said device, or by the reversing pinion of the said gear 25 box. It provides for a twofold use of the range of speeds furnished by the said box, and for this reason the change-speed device according to this invention is especially advantageous for use upon portable power 30 plants of the tractor type which are required to operate at full load and reduced speed at the working yard or at a railway station, or the like, but on the other hand are required to travel rapidly from one working point 35 to another either separately or with a light trailer load.

Two forms of construction of the invention as applied to a tractor of the said type are shown by way of example in the accompanying drawings, wherein:

Fig. 1 is a view partly in section and partly in elevation of a change-speed device for two speeds actuated by a spur gear of any suitable kind.

50 Figs. 2 and 3 are detail views showing in separate disposition the manner in which the shifting device moves one or the other of the two pinions which engage the clutch member.

Fig. 4 is a view partly in section and partly in elevation showing the change-speed device for two speeds disposed at the end of a first change-speed box and controlled by the reversing pinion of the latter change-speed box, and Fig. 5 is a view partly in section and partly in elevation showing a further form of construction of the invention.

The casing 1 containing the whole change-speed device is traversed by the main actuated shaft 2 which is for instance terminated at either end by a sprocket wheel which drives respectively by chain one of the axles of the power tractor. To the shaft 2 within the casing is keyed a clutch member 3 having on each side the internal gear teeth 4 and 5. Upon the shaft 2, on either side of the clutch member 3, are loosely mounted two gear wheels of considerably different diameters 6, 7. The large diameter gear wheel 6 is provided with the spur gear teeth 8 and also with a second set of spur gear teeth 9 adapted to engage the internal teeth 5 of the clutch member 3. This second set of teeth is shown in dotted lines in Fig. 1, the section in this figure being taken between two teeth of the said set, and this is also shown in Fig. 4. The gear wheel 7 may engage with the teeth 4 of the clutch member 3, or with a gear wheel 10 which is loosely mounted upon two ball bearings 11 about a portion of shaft 12 secured within the casing 1. The gear wheels 6 and 10 are both constantly actuated by a shaft 14 driven by the engine in any suitable manner.

The casing 1 is also traversed by a rod 15 which may be moved by means of a suitable device in the sense of one or the other of the arrows 16, 17. The said rod has mounted thereon by hubs secured by bolts two control forks 18, 19. The fork 18, Figs. 1 and 3, actuates the gear wheel 6 by engaging a groove 20 of the hub 21. The fork 19, Figs. 1 and 2, has a double form and actuates both the gear wheel 7 and the intermediate gear wheel 10, engaging respectively the circular grooves 22, 23 of the said gear wheels.

The operation of the device is as follows: The gear wheel 13 constantly drives the gear wheels 6, 10 and the latter constantly drives the gear wheel 7. By moving the rod 15 of the forks in the proper direction, the gear wheels 6 or 7 are caused to engage the

clutch device 3. The actuated shaft 2 having secured thereto the clutch device 3 is thereby driven at one or the other of the speeds corresponding to the diameters of the gear wheels 6, 7. The reversal of rotation of the shaft 2 is effected by the reversal of the motion of the gear wheel 13.

Fig. 4 represents a change-speed box of this character disposed after a first change-speed box. In this case the gear wheels 6, 10 are driven by a gear wheel 24 secured to a shaft 25 by means of the fluted portions 26 and slidable on the said shaft. The gear wheel 24 has formed therein a circular groove 27 engaging a fork 28 controlled by a lever 29 whereby the gear wheel 24 is caused to slide upon the shaft 25. On the latter shaft and on either side of the wheel 24 are loosely mounted two symmetrical bevel gears 32, 33 which are constantly engaged by the bevel teeth with a bevel pinion, not shown, situated perpendicular to the plane of the figure, and mounted on the outgoing shaft of the first change-speed box. The wheels 32, 33 are thus constantly driven in the contrary sense. These two wheels are each provided with internal teeth of spur type adapted to engage the gear wheel 24. According to the engagement of one or the other of the wheels 32, 33 with the gear wheel 24, the latter will be rotated in one sense or the other, and will drive in the same sense the main actuated shaft 2. The whole device is mounted upon two ball-bearings 30 and 31 situated at the ends of the shaft 25. In the form of construction shown in Fig. 4, two brake drums 34, 35 are secured at the ends of the shaft 25 and are in a constant mechanical relation with the main actuated shaft.

The form of construction above set forth has the following drawbacks:

1. The intermediate actuating pinion is mounted on a portion of shaft in overhang position and therefore operating under defective conditions.
2. The said clutch member is provided with two sets of internal teeth whereof one set adjacent the sleeve used for the mounting upon the main actuated shaft is difficult to construct by machine.

The form of construction shown in Fig. 5 is exempt from the above-mentioned drawbacks. The common driving wheel actuates the two gear wheels of different diameters mounted loose on the main actuated shaft, through the intermediary of a set of gear wheels mounted loose on a shaft journaled at the ends thereof. The diameters and the number of teeth of the said gearing are so calculated as to provide for the requisite speed reduction ratios. The said device enables the construction of a clutch member having a single set of internal teeth on the side opposite the said sleeve, and an external

set of teeth. At the same time, the width of the whole apparatus can be reduced in a considerable degree.

Within the casing 36 is keyed to the main actuated shaft 37 the clutch member constituted of a double-faced disk 38 having a set of internal teeth 39 and a set of external teeth 40. On either side of the clutch member 38 are loosely mounted on the shaft 37 the two gear wheels 41 and 42 of different diameters, controlled respectively by the forks 43, 44 and adapted to separately engage one or the other of the sets of teeth of the clutch member 38. The gear wheel 41 engages a gear wheel 45 and the gear wheel 42 engages a gear wheel 46 pertaining to a set of gear wheels keyed to the shaft 47 which rotates in the bearings 48 provided in the casing 36 through the intermediary of the ball-bearings 49.

The gear wheel 46 engages the actuating pinion 50 of the device, the latter being keyed to the shaft 51 which is driven by any suitable motor or engine or extends outwardly of another change-speed box which is in turn connected with any suitable motor or engine. The gear wheels 50 and 42 have for instance the same number of teeth, and it is no longer necessary, as in the form of construction shown in Fig. 1, that there shall be a great difference in the diameters of the gear wheels 41 and 42, inasmuch as there is provided a two fold speed reduction, firstly between the gearing 50 and 46 and secondly between the gearing 45 and 41.

This combination of two change-speed devices mounted in series is especially advantageous for portable power plants of the tractor type. It enables the use of the four or six speeds of the first change-speed box in two different ways, firstly by a method of operating at speeds of the order of 12 kilometres an hour for instance, for full load working at the place of use, and secondly by a method of operating at speeds of the order of 40 kilometres an hour for travel from one working point to the other and for transportation of workmen.

What I claim is:

1. A change speed gear having two ratios and its gear wheels constantly in mesh comprising in combination, a driving shaft, a common driving gear keyed to said shaft, a driven shaft, a double faced gear clutch disk keyed to the driven shaft, two final gears corresponding to the two ratios loosely mounted on the said driven shaft and constantly actuated by the common driving gear, one of the final gears having a single set of spur gear teeth for simultaneously engaging a gear which turns it, and the double faced gear clutch disk, and means for shifting respectively the final gears along the driven shaft whereby either of the gears is caused to engage the said clutch disk.

2. A change speed gear having two ratios and its gear wheels constantly in mesh comprising in combination the outgoing shaft of another ordinary change speed device, a common driving gear keyed to said shaft, a driven shaft a double faced gear clutch disk keyed to the driven shaft, two final gears corresponding to the two ratios loosely mounted on the said driven shaft and constantly actuated by the common driving gear, one of the final gears having a single set of spur gear teeth for simultaneously engaging a gear which turns it, and the double faced gear clutch disk, and means for shifting respectively the final gears along the driven shaft whereby either of said gears is caused to engage the said clutch.

3. A change speed gear having two ratios and its gear wheels constantly in mesh, comprising in combination, a driving shaft, a driving gear keyed to said shaft, a driven shaft parallel to the driving shaft, a double faced gear clutch disk keyed to the driven shaft having internal teeth and external spur teeth superimposed on the internal teeth, two final gears corresponding to the two ratios loosely mounted on the said driven shaft, one of the final gears having a single set of spur gear teeth for simultaneously engaging a gear which turns it, and the double faced gear clutch disk, an intermediate shaft parallel to the driving shaft and to the driven shaft, a set of gearing, actuated by the driving gear, on the said intermediate shaft and comprising two gear wheels, one of which engages simultaneously with the driving gear and with one of the final gears, the other engaging with the other final gear, and means for shifting respectively the final gears along the driven shaft whereby either of said gears is caused to engage the said clutch disk.

with the driving gear and with one of the final gears, the other engaging with the other final gear, and means for shifting respectively the final gears along the driven shaft whereby either of said gears is caused to engage the said clutch disk.

4. A change speed gear having two ratios and its gear wheels constantly in mesh comprising in combination the outgoing shaft of another ordinary change speed device, a driving gear keyed to said shaft, a driven shaft parallel to the driving shaft, a double faced gear clutch disk keyed to the driven shaft having internal teeth and external spur teeth superimposed on the internal teeth, two final gears corresponding to the two ratios loosely mounted on the said driven shaft, one of the final gears having a single set of spur gear teeth for simultaneously engaging a gear which turns it, and the double faced gear clutch disk, an intermediate shaft parallel to the driving shaft and to the driven shaft, a set of gearing, actuated by the driving gear, on the said intermediate shaft and comprising two gear wheels, one of which engages simultaneously with the driving gear and with one of the final gears, the other engaging with the other final gear, and means for shifting respectively the final gears along the driven shaft whereby either of said gears is caused to engage the said clutch disk.

In witness whereof I have hereunto set my hand.

PIERRE DONON.
